UNITED STATES PATENT OFFICE.

ALEXANDER McCLEARY, OF DENVER, COLORADO, ASSIGNOR OF ONE-HALF
TO FRANK DAVID THOMPSON AND WELLINGTON STANLEY KORFHAGE,
OF DENVER, COLORADO.

LOCK.

No. 837,946.

Specification of Letters Patent.

Patented Dec. 11, 1906.

Application filed June 7, 1905. Serial No. 264,155.

To all whom it may concern:

Be it known that I, ALEXANDER McCLEARY, a citizen of the United States of America, residing at Denver, in the county of Denver and State of Colorado, have invented certain new and useful Improvements in Locks, of which the following is a specification.

This invention, which relates to improvements in spring or draw-bolt locks, has for its object the provision of a simple, easily-operated, and highly-effective lock of the class named which, being entirely composed of cylindrical and circular shaped parts, may readily be put in place and adjusted on a door by means of an ordinary auger and without the use of chisels or similar tools. I attain this object by the mechanism illustrated in the accompanying drawings, in the various views of which like parts are similarly indicated, and in which—

Figure 1 represents a vertical section through a door and jamb, showing my lock in place and its casing in section; Fig. 2, a horizontal section taken along the line 2, 25 Fig. 1, the draw-bolt, knob, spindle, and key-bolt being shown in elevation; Fig. 3, a cross-section along line 3, 3, Fig. 2, looking in the direction of the arrow; Fig. 4, a cross-section along line 4, 4, Fig. 2; Fig. 5, a cross-section 30 along line 5, 5, Fig. 2; Fig. 6, a fragmentary perspective view of the lower part of the key used to operate the pinion-spindle of my lock, and Fig. 7 a similar view of one of the extremities of the key-bolt.

35 My lock comprises a tubular barrel or housing 5 and a cylindrical draw-bolt 6, having a longitudinally-rectilinear reciprocating movement therein and maintained in the extended or locked position by a tension-spring 40 7. Bolt 6 is provided at its outer extremity with the square and beveled head 8, normally extending in a correspondingly-shaped recess 9 in the door-jamb 10. This recess, like the other mortises required to place my lock, 45 is made cylindrical and is protected by the strike-plate 11, which may also be made circular in outline. When the bolt is retracted, head 8 enters a correspondingly-shaped recess 12, formed in the enlarged outer extremity 13 of barrel 5. Head 8 being larger than the main body of the bolt forms a shoulder 14, while a thumb-screw 15, passing through a cylindrical opening 16 in door 17, projects into a correspondingly-tapped aperture 18

in the enlarged part 13 of casing 5. Screw 15, being located on the inside of the door, constitutes the night-latch, by which the bolt may be locked against retraction by either knob or key. When it is desired to thus secure the door, thumb-screw 15 is turned to project into recess 12 in the path of the shoulder 14 of head 8, which engaging the protruding end of the screw arrests further inward movement of the bolt. The innermost extremity 19 of bolt 6 has been reduced to form a shoulder 20 for the spiral spring 7, which being placed around the reduced portion engages said shoulder and the end plate 21 of barrel 5. The outer extremity of the reduced end 19 of the bolt is threaded and projects beyond the end plate 21, where a nut 22, screwed onto said extremity, limits the outward movement of the bolt. Nut 22, furthermore, affords means to regulate the length of stroke of the bolt as well as the tension of spring 7.

Bolt 6 may be retracted by turning knobs 23, located at each side of door 17 and mounted on a spindle 24, which passes through corresponding apertures 25 and 25. A toothed 80 pinion 26, rigidly mounted on this spindle, extends through an opening 6^a in the casing and engages a rack 27, which extends along the upper surface of bolt 6.

To lock door 17, it is essential that the bolt 85 should be firmly held against linear movement. This object may be accomplished from either side by means of the cylindrical key-bolt 28, which extends transversely of bolt 6 through apertures 29, 29 in door 17. 90

When in the locking position, bolt 28 projects through a correspondingly-formed notch or recess 30 in the upper surface of bolt 6, as illustrated in Figs. 1, 2, and 5. The central portion of bolt 28, extending over 95 the draw-bolt, has also been provided with a similar recess or depression 31 of a depth sufficient to bring the peripheral surface of the key-bolt out of engagement with the recess in the draw-bolt when the former has been turned to bring the two recesses opposite each other. Placed on each side of door 17 are the customary escutcheons 32, having openings 33, through which the knob-spindle projects, and apertures 34, through which 100 the key 38, operating bolt 28, may be introduced. Apertures 34 extend through outwardly-extending cylindrical projections 35

on the escutcheons, having similarly-shaped recesses 36 on their inner surface for the accommodation of projections 37 on the key 38.

It will be understood that the form or con-

5 struction of the working end of the key may be varied, so that no two shall be alike, and that the aperture 34, as well as the apertures 39 in the ends of the key-bolt, are made to conform with the construction of the particu-
10 lar key provided for the lock of which they form part.

15 The key, as shown in Fig. 3, has a cylindrical extremity or pin 38^a, provided with opposite transversely-extending lugs 37, and apertures 34 in the escutcheons and 39 in the key-bolt are shaped to permit the passage of pin 38^a, as well as its projections 37.

20 To turn key-bolt 28, key 38 is inserted in one of the apertures 34 until lugs 37 extend in the circular recess 36. The key is now turned until the projections 37 are brought in register with the correspondingly-shaped clefts or grooves 39^a of aperture 39 in the key-bolt, in which they may be inserted by 25 pressing key 38 inwardly.

25 Key-bolt 28 is retained in the locked and unlocked positions by means of a weak, preferably wire, spring 47, which being held at its upper extremity 48 in a recess 46 in door 30 17 extends downwardly and projects into the uppermost cleft of the aperture 39 at one of the ends of the key-bolt.

35 When the bolt is being turned, the extremity of spring 47, leaving groove 39^a, rides along the periphery of the bolt until the opposite cleft has attained its uppermost position.

40 It will be observed that half a revolution of bolt 28 in either direction brings it from the locked to the unlocked position, and vice versa.

45 The operation of my device will be readily understood from the foregoing description and the accompanying drawings.

45 The beveled latch-bolt being maintained in its extended position by the spring 7 may readily be withdrawn by means of knobs 23 through instrumentality of the pinion and rack.

50 When locked by key 38 or thumb-screw 15, the bolt may be released from either side by action of the key and key-bolt or by withdrawing screw 15 on the inside of the door, while the corresponding construction of the

apertures in the escutcheons and the key- 55 bolt and the working end of the key prevents opening of the lock by any but its own proper key.

To place the lock in the door, three concentric recesses 40, 41, and 42 are drilled to 60 permit insertion of the tubular housing 5 and the protruding extremity of bolt 6 with nut 22. Similar holes 25 and 29 are drilled for spindle 24 of knobs 23 and for the key-bolt, while shallow cylindrical recesses drilled at 65 each side of the barrel-hole in the edge of the door afford accommodation for the correspondingly-shaped selvage or face-plate 43.

The entire structure is held in place by the escutcheons 32, secured by screws 44, and 70 by screws 45, passing through the face-plate.

Having thus described my invention, what I claim is—

1. A lock comprising a tubular housing, a cylindrical draw-bolt therein, having a reduced rear end, and an arc-shaped recess 75 30, a rack on said bolt, a spindle, a pinion thereon engaging with the rack to reciprocate the bolt, a key-bolt extending transversely of said draw-bolt and through the arc-shaped 80 recess therein, said key-bolt having a corresponding recess therein, escutcheons having openings therein for the passage of the spindle, and also having cylindrical projections 85 thereon extending over the ends of the key-bolt to hold the same in place; a key for turning the key-bolt to bring the recess therein opposite the recess in the draw-bolt, said projections on the escutcheons having openings 90 therein for the passage of the key and a spring on the reduced end of the draw-bolt having its ends bearing against the said bolt and a part of the housing.

2. A lock comprising a tubular housing, a draw-bolt having a reciprocating movement 95 therein, means to shoot and retract said bolt, a key-bolt extending transversely of said draw-bolt through a peripheral recess thereof and adapted to be turned out of engagement therewith, and a spring projecting into one 100 of a plurality of suitable recesses in said bolt.

In testimony whereof I have affixed my signature in presence of two witnesses.

ALEXANDER McCLEARY.
